UNITED STATES PATENT OFFICE

93,012

DESIGN FOR A BURIAL CASKET

Juil R. Goggins, Minneapolis, Minn.

Application May 7, 1934, Serial No. 51,708

Term of patent 14 years

To all whom it may concern:

Be it known that I, JUIL R. GOOGINS, a citizen of the United States, residing at Minneapolis, in the county of Hennepin and State of Minnesota have invented a new, original, and ornamental Design for Burial Caskets, of which the following is a specification, reference being had to the accompanying drawing forming part thereof.

Fig. 1 is a perspective view of a burial casket, showing my new design. Fig. 2 is a side elevational view.

I claim:

The ornamental design for a burial casket as shown.

In testimony whereof I hereunto affix my signature.

JUIL R. GOOGINS.
